UNITED STATES PATENT OFFICE.

CHARLES HENRY EASTE, OF ARLINGTON, MASSACHUSETTS.

COMBINED CHAIR AND DESK.

SPECIFICATION forming part of Letters Patent No. 446,632, dated February 17, 1891.

Application filed July 31, 1890. Serial No. 360,507. (No model.)

To all whom it may concern:

Be it known that I, CHARLES HENRY EASTE, a citizen of the United States, residing at Arlington, in the county of Middlesex and 5 State of Massachusetts, have invented a new and useful Combined Chair and Desk, of which the following is a specification.

This invention has relation to that class of furniture known as "convertible."

10 The objects of the invention are to provide a combined chair and writing-desk with all the conveniences and appurtenances of both, and when used as a chair to have the appearance only as such and to be adapted for a 15 ready conversion.

With the above objects in view the invention consists in certain features of construction hereinafter specified, and particularly pointed out in the claim.

20 Referring to the drawings, Figure 1 is a perspective of a combined writing-desk and chair constructed in accordance with my invention, the same being shown as a chair. Fig. 2 is a similar view, the same being shown 25 as a writing-desk. Fig. 3 is a top plan of Fig. 2, the desk being opened. Fig. 4 is a vertical longitudinal section.

Like numerals of reference indicate like parts in all the figures of the drawings.

30 In practicing my invention I may employ any ordinary chair, the only requisite being that it is sufficiently stout to lend stability and steadiness, and comprises a pair of rear standards or posts, which usually form a part 35 of the backs of chairs.

In the present instance, 1 designates the chair seat and frame, the latter supported by the front legs 2 and the rear legs 3 extended above the chair-seat to form the usual back 40 standards 5. This seat is suitably upholstered and may be of any desired design and finish, and below the seat proper the fore legs support a rectangular frame 6, provided at the back of the chair with an opening 7 and 45 at opposite sides with suitable ways 9. In the opening and upon the ways is mounted a drawer 8, having a suitable pull, said drawer being designed for the reception of stationary of various kinds, correspondence, &c.

50 10 designates a writing-desk subdivided by a transverse partition 11 to form a large stationary receiving-compartment 12, and an up-

per smaller space trisected by transverse partitions 13, forming a central pen-receiving space 15 and ink-receiving spaces 14. The 55 desk may of course be otherwise divided to suit the fancy of the maker and the purpose intended. The space 12 is covered by a hinged lid 16, and the upper spaces 15 and 14 by a second smaller lid 17, hinged to the upper end 60 of the desk-frame. The lid 16 serves as a writing-space, and may be covered with a suitable material, such as leather, baize, &c., and is maintained in a locked position by means of a swiveled L-shaped bolt 18 or any 65 other suitable catch. The desk serves as such and also as a back of the chair, and for this reason has its front face upholstered, as at 19, to correspond with the upholstery of the seat. Bolts 20 pass laterally through each of 70 the rear standards 5 and take into the opposite sides of the desk, so that the latter is pivoted in position.

21 designates a pair of turn-buttons pivoted, as at 23, to the rear edge of the seat-frame and adapted to be turned to a vertical position and extend above said frame in rear of the desk, and thus maintain the same rigidly in a vertical position, so as to serve as a back. Simultaneous movement upon the 80 part of the buttons is secured by means of a connecting-rod 22, loosely pivoted at its ends to the corresponding free ends of the buttons.

24 designates a pair of jointed braces, the ends of which are pivoted, as at 25, to the 85 sides of the desk near its lower end and to the inner sides of the standards 5 at points just above the seat. The braces are formed in sections and pivoted together at their inner ends, the upper brace having a recess 26 upon its 90 front edge, into which takes a lug or stop 27, formed upon the upper end at the similar side of the lower brace, so that when the two brace-sections are brought into parallelism or alignment they can move no further, and are as 95 rigid as if formed integral. In this manner the desk may be supported at a proper inclination and adapted to be written upon. It will be understood that the interior of the desk will be provided with all the accessories 100 necessary to a complete writing outfit, and the under side of the cover may be provided with a portfolio or pocket 28 for the convenience of the writer. When the writing opera-

tion has been completed, the desk is closed and is swung to a vertical position, the braces readily yielding at their joints and folding, as shown, after which the buttons 21 are swung 5 to a vertical position and the writing-desk is transformed into an ordinary-looking chair.

It will be observed that the turn-buttons 21 when in a vertical position not only serve to retain the chair-back in position, but also as 10 a lock for the drawer, so that said chair may be moved about in the same manner as an ordinary chair without any danger of spilling the contents.

Having thus described my invention, what I 15 claim is—

The combination, with a chair-frame comprising a pair of rear vertical standards, of

a combined writing-desk and back pivoted between the standards, the opposite pairs of pivoted brace-sections pivoted at their ends 20 to the combined back and desk and to the chair-frame, means for locking said sections in alignment, and the turn-buttons pivoted to the rear end of the frame and adapted to overlap the lower end of the combined back 25 and desk, substantially as specified.

In testimony that I claim the foregoing as my own I have hereto affixed my signature in presence of two witnesses.

CHARLES HENRY EASTE.
